UNITED STATES PATENT OFFICE.

ISAAC H. GARSON, OF ROCHESTER, NEW YORK, ASSIGNOR TO THE GARSON VENDING MACHINE COMPANY, A CORPORATION OF NEW JERSEY.

CIGAR-VENDING MACHINE.

No. 842,143.

Specification of Letters Patent.

Patented Jan. 22, 1907.

Application filed December 16, 1904. Serial No. 237,138.

To all whom it may concern:

Be it known that I, ISAAC H. GARSON, of Rochester, in the county of Monroe and State of New York, have invented certain new and useful Improvements in Cigar-Vending Machines; and I do hereby declare the following to be a full, clear, and exact description of the same, reference being had to the accompanying drawings, forming a part of this specification, and to the reference-numerals marked thereon.

My present invention relates to improvements in vending-machines of that kind which are particularly adapted for use in vending and handling cigars and analogous articles, and it is the purpose of my invention to provide a device of this character which is capable of delivering the cigars or other articles to the purchaser directly from the original stamped package without liability of becoming broken or otherwise injured and in such numbers or quantity as will be determined by the value of the coin which may be inserted by the purchaser, mechanism being employed which will retain the delivery mechanism unlocked or capable of further operation without requiring insertion of another coin should the supply of cigars or other articles become exhausted either prior to or during the operation of the device; and to these and other ends it consists in certain improvements and combinations and arrangements of parts that will be hereinafter more fully explained, the novel features being 35 pointed out particularly in the claims hereunto annexed.

In the drawings, Figure 1 is a plan view of a vending-machine constructed in accordance with my invention, the top of the casing being removed. Fig. 2 is a vertical sectional view of the same on the line 2 2 of Fig. 1. Fig. 3 is a vertical sectional view on the line 3 3 of Fig. 1 looking in the direction of the arrow. Fig. 4 is a sectional view through a portion of the casing, showing the coin-chutes and contiguous parts on an enlarged scale. Fig. 5 is a fragmentary view showing the locking device for the drawer on an enlarged scale. Fig. 6 is a view in elevation of the coin-actuated devices for locking and unlocking the delivery mechanism. Fig. 7 is a view similar to Fig. 6, showing the arrangement of the devices for locking and unlocking the drawer. Fig. 8 is a sectional view on the

line 8 8 of Fig. 3 looking in the direction of the arrow, showing the actuating device for the delivery mechanism previous to operation; and Fig. 9 is a view similar to Fig. 8, showing the relative positions of the parts subsequent to operation. Fig. 10 is a sectional view on the line 10 10 of Fig. 3 looking in the direction of the arrow, the parts being shown in their normal locked positions; and Fig. 11 is a view similar to Fig. 10, showing the relative positions of the parts after being unlocked.

Similar reference-numerals in the several figures indicate similar parts.

A vending-machine which is particularly adapted for use in vending cigars and similar articles which embodies my improvements comprises a casing 1, which may be of any desired configuration and dimensions, which is preferably rendered transparent by the use of the panels 2, which may be composed of glass or other transparent material, which inclose the sides and top of the casing, a hinged or removable closure 3 being provided, preferably at the top of the casing, for the purpose of permitting access to the interior thereof. The lower portion of the casing is preferably composed of a box 4, which is adapted to contain a portion of the mechanism of the machine and is separated from the upper portion of the casing by a partition 5, the latter being provided with an aperture 6, within which is fitted a hopper 7, the exterior dimensions of which are such as to permit it to enter between the sides of an ordinary cigar box or receptacle 8 from which the top or bottom has been previously removed, it being preferable in the present instance to remove the bottom of the box and place the latter over the hopper, with its cover or lid 9 opened and supported against the relatively inclined support 10 of the casing in the manner shown in Figs. 1, 2, and 3, for this enables the cigars to be exhibited in their original form and package to the purchaser and permits ready inspection of the package and its contents by the revenue officials, as required by the revenue laws. The hopper 7 preferably extends only partially into the box or receptacle, and for the purpose of supporting the box in the proper position the flange 11 may be employed, which surrounds the hopper and forms an abutment for the lower edges of the box.

The bottom of the hopper 7 is inclined from its ends toward its center, where it is provided with the elongated aperture 12, beneath which operates a carrier 13, which is mounted on a sleeve 14, revolvably fitted over the shaft 15, the periphery of the carrier 13 being provided with a series of axially-arranged pockets 16, which are so formed as to readily receive a cigar of ordinary dimensions, rollers or other antifriction devices 17 being preferably fitted in the walls of the pockets to enable the cigars to readily enter and leave the pockets of the carrier with the slightest friction and pressure, a similar roller 17^a being employed on the adjacent edge of the hopper 7, if desirable, to facilitate the passage of the cigar from the carrier. At one side of the carrier 13 is provided a receptacle for the reception of the articles from the carrier, a slideable drawer 18 being employed in the present instance which is capable of being withdrawn from the casing of the machine by the purchaser when one or more cigars or other articles have been deposited therein by the carrier. At the opposite side of the carrier 13 are mounted the agitating devices, which are preferably employed for arranging the cigars or other articles within the hopper so that they will properly enter the carrier, and in the present instance they embody the curved fingers 19 19, which are mounted on a rotatable shaft 20 and are arranged to operate through the corresponding slots 21 21, formed in the bottom of the hopper, the carrier 13 being divided into separated sections to enable the extremities of these agitating-fingers to partially enter the pockets thereof as they are carried past the discharge-aperture of the hopper, and as these fingers are lifted, in a manner that will hereinafter appear, the cigar which is adjacent thereto will gradually slide over the curved portion thereof until it rests in the adjacent pocket of the carrier, the release of the fingers causing them to suddenly drop back, and thereby bring another cigar into operative position to enter the carrier at the next succeeding operation.

Between the separated sections of the carrier 13 are arranged the arms 22 22, which are each provided with a slot or aperture 23 to receive the sleeve 14 as a support, about which the said arms may move as a fulcrum, the upper end of each arm being so arranged as to be engaged by each cigar in its corresponding pocket of the carrier prior to its discharge therefrom to cause a tilting motion of the arms, and as the opposite ends of these arms are connected to the crank 24, which is fixed to a rock-shaft 25, an oscillatory motion will be thereby imparted to the latter, which will cause the crank 26, which is fixed to the opposite end thereof, to be elevated. This crank 26 is provided with a pin 27, to which is attached a link 28, which

forms a connection with the crank 29, the latter being fixed to a rock-shaft 30, which is provided with the radially-disposed arms 31 and 32, respectively. Above the arm 31 terminates the lower extremity of a coin-chute 33, which discharges into the coin-receptacle 34 of a pivoted coin-actuated member 35, the said receptacle being open at one side and provided with a projection 36, which will temporarily support a coin of the proper diameter within the receptacle to cause the member 35 to move into the position shown in dotted lines in Fig. 10, an aperture being provided in the receptacle to receive the arm 31, the inclined end of which will engage the coin and eject it laterally from the receptacle, permitting the member 35 to be restored to its normal position beneath the chute under the action of its counterweight 37. The coin-actuated member 38 is similarly provided with a coin-receptacle 39, which is arranged to normally occupy a position beneath its corresponding chute 40, the arm 32 of the shaft when actuated operating in a manner similar to the arm 31 to discharge the coin from its respective receptacle, and thereby permitting the corresponding member 38 to be restored to normal position under the action of its counterweight 41.

The coin-actuated member 38 is provided with an offset projection 38^a, which is so arranged as to coöperate with the adjacent member 35 to simultaneously actuate the latter when the member 38 is depressed, and to the member 35 is attached a link 42, which forms a connection with the crank 43, fixed to the rock-shaft 44, and to the latter is fixed a controlling-arm 45, which is curved and adapted to normally operate as a rest or guard, which coöperates with a lateral projection 46 of a pawl 47 to retain the latter out of coöperative relation with a ratchet-wheel 48, the latter being fixed to the sleeve 14, which carries the carrier 13 and serves to actuate the latter, and the pawl 47 is pivotally mounted upon an arm 49, which is fixed to the operating-shaft 15, an arm 51 being provided upon the said shaft to operate between the relatively fixed stops 52 and 53 to permit the pawl to travel only the distance of one tooth of the ratchet at each actuation of the operating-shaft 15. However, depression of the member 35 will operate through the connection 42 to rock the shaft 44, thereby depressing the controlling-arm 45 and permitting the pawl 47 to coöperate with the ratchet 48, causing motion to be transmitted thereto from the operating-shaft, resetting of the member 35 causing the arm 45 to be returned to its normal position to disengage the pawl 47 from coöperative relation with its ratchet 48. Of course through the connection 38^a, which serves to actuate the member 35 when the member 38 is depressed, the arm 45 will be similarly ac-

tuated, and it will not return to its normal position until the member 38 has been reset.

To the coin-actuated member 38 is attached a link 54, which forms a connection with a pivoted detent 55, the free end of which is provided with a projection 56, which is arranged to engage the peripheral notches or recesses 57, which are formed in the disk 58, the latter being revolubly mounted on the operating-shaft 15 and provided with a series of equidistantly-spaced projections 59, which are arranged to coöperate with a detent 60, which is pivoted to a relatively fixed portion of the machine and is operated under the yielding action of the spring 61, that portion of the detent which coöperates with the projections of the disk 58 being provided, preferably, with oppositely-inclined surfaces for properly positioning the said disk at its different positions of rotation. The disk 58 is also provided with a series of projections 62, which coöperate with a pawl 63, while the latter occupies a predetermined position to positively prevent rotation of the said disk, and as this pawl 63 is fixed to the rock-shaft 64, which is connected by the arm 65 to the pin 27 of the operating-arm 26, the said pawl will be disengaged from the projections of the disk 58 to permit rotation of the latter each time the arms 22 are operated by a cigar while being discharged from the carrier, and unless there is a cigar to be discharged by the carrier the pawl 63 will lock the disk 58 from rotation. When the detent 55 has been disengaged from its corresponding notch 57 in the disk 58 and the latter has been rotated, the projection of the detent will ride upon the periphery of the disk, and this will retain the members 38 and 35 depressed, and through the link 42, which is connected to the latter, the controlling-arm 45 will be depressed, and thereby permitting the pawl 47 to coöperate with the ratchet 48 to actuate the latter.

To the operating-shaft 15 is fixed an arm 66, to one end of which is attached the spiral spring 67, the opposite end of the said arm being arranged to coöperate with a pin 68, to which the opposite end of the spring 67 is attached and which is fixed to an arm 69, the latter being rotatably mounted on the shaft 15 and provided with a pawl 70, which is arranged to coöperate with the projections 62 of the disk 58 to actuate the latter, the spring 67 forming a yielding connection between the operating-shaft 15 and the pawl-arm 69 to cause the disk to be actuated when the operating-shaft is rotated while the detent 55 is unlocked from the disk, it being obvious that operation of the shaft 15 while the disk 58 is locked by the detent 55 would fail to operate the disk, as the spring 67 forms a yielding connection between the shaft and the pawl-arm 69 and would permit the latter to remain stationary while the arm 66, which

is fixed to the operating-shaft, disengages from the pin 68.

For the purpose of returning the operating-shaft 15 to its normal position after being operated a spring 71 may be employed, one end of which is attached to the shaft, and the other end is attached to a relatively fixed portion of the machine.

To the sleeve 14, which operates the carrier, is fixed a toothed disk or cam 72, with which coöperates a roller or projection 73, which is attached to a pivoted lever 74, the latter being normally held in operative engagement with the cam by the spring 75, which will operate to resist the rotation of the carrier, and it is provided at its free end with a link 76, which serves to connect the said lever with the lever 77 and the crank 78. The lever 77 is pivoted at 79 and provided at its opposite end with a plunger 80, which is arranged to coöperate with the locking device for the drawer, the said device embodying in the present instance a flexible arm 81, which is fixed at one end to the rear portion of the drawer, the free end being provided with a shoulder 82, which is adapted to detachably engage the adjacent portion 83 of the casing to prevent the removal of the drawer, the plunger 80 operating to depress the arm 81, and thereby unlock the shoulder 82 from the corresponding abutment formed by the casing, and for the purpose of preventing the premature relocking of the drawer I prefer to employ the spring 84, which serves to actuate the drawer forwardly immediately after being unlocked.

Assuming that a box or package of cigars the bottom of which has been previously removed is fitted over the hopper 7 in the manner shown in Figs. 1, 2, and 3, it will be understood that the carrier which controls the delivery of the cigars is inoperative, for until a coin of the proper denomination is inserted in its corresponding chute the controlling-arm 45 will retain the actuating-pawl 47 out of operative engagement with the ratchet 48, through the operation of which the carrier is rotated, even though the operating-shaft 15 may be freely rotated by the crank 85, which is conveniently located exteriorly of the casing. However, assuming that a coin of the proper denomination has been deposited in the chute 33 it will be obvious that it will descend the latter and drop into the receptacle 34, which is carried by the movable member 35, causing the latter to be depressed, and as the link 42 connects this member with the rock-shaft 44, to which the controlling-arm 45 is attached, the latter will in turn be depressed sufficiently to permit the actuating-pawl 47 to coöperate with the ratchet 48, and when the operating-shaft 15 is rotated by the crank 85 it will cause the actuating-arm 49 thereon, which carries the pawl 47, to impart a corresponding rotary

motion to the ratchet 48, and as the latter is fixed to the sleeve 14, which carries the carrier 13, a corresponding rotary motion will be imparted to the carrier, causing the foremost 5 cigar, which rests in a corresponding pocket of the carrier, to move toward the drawer 18, and while the cigar is being thus advanced it will engage the adjacent ends of the arms 22, producing a rocking motion of the latter, 10 which will be transmitted, through the crank 24, to the shaft 25, and the rocking motion thus imparted to the latter will be transmitted to the crank 26. As the rock-shaft 30 is operatively connected to the crank 26 15 through the crank 29, link 28, and the pin 27, it will be obvious that the cigar before passing from the carrier will cause operation of the shaft 30 and its fingers 31 and 32, and as the finger 31 is arranged to enter the coin- 20 receptacle 34 of the member 35 while the latter is depressed by the coin the coin will be obviously released from the receptacle to permit the member 35 to return to its normal position, and in doing so it will reset the 25 controlling-arm 45, thereby preventing the subsequent operation of the shaft 15 from operating the carrier to deliver another cigar unless another coin is inserted. Thus it will be understood that unless there is a cigar in 30 the carrier ready for delivery the arms 22 will not be operated, and consequently the coin will not be ejected from its corresponding coin-receptacle, and this will leave the machine unlocked, or, in other words, with 35 the operating-shaft and carrier operatively connected, so that the article-delivering carrier may be operated by the customer until it has been refilled, when the first cigar delivered by the carrier will operate to eject the 40 coin and relock the machine—that is, the operating-shaft and carrier will be disconnected or otherwise placed in such condition that the delivery-carrier cannot be operated by the customer unless the requisite coin is 45 inserted.

While the carrier is operating to deliver a cigar, the cam 72, which is mounted to rotate therewith, will operate upon the roller or projection 73 to oscillate the arm 74, and as 50 the latter is connected through the link 76 to the lever 77 and the crank 78 the locking device 81 will be disengaged from the abutment 83 by the depression of the plunger 80, thereby unlocking the drawer 18 to permit withdrawal thereof, and thus render the articles delivered by the carrier 13 accessible to the purchaser. Simultaneously with the unlocking of the drawer the crank 78, which is also actuated by the cam 72, will oscillate the 55 shaft 20, thereby causing the agitating-fingers 19, which are carried thereby, to be oscillated through the slots 21 in the hopper, the successive operation of these fingers operating upon the cigars in the hopper to cause 60 them to properly arrange themselves in read-

iness to enter the longitudinal pockets of the carrier. The roller or projection 73 will return to the relative position shown in Fig. 7 when the delivery of the cigar has been completed by the carrier, and as the drawer 18 is returned within the casing the flexible arm 81 will automatically spring into position to lock the drawer, the plunger 80 at this time being elevated.

Assuming that a coin of relatively higher 75 value is deposited in the chute 40, it will be obvious that it will enter the receptacle 39 of the member 38, causing the latter to be depressed, which in turn will depress the member 35 through the connection 38^a, the member 35 operating to depress the controlling-arm 45 in a manner hereinbefore described to establish an operative connection between the operating-shaft 15 and the carrier 13 80 through the arm 49 and actuating-pawl 47, 85 and the ratchet 48, and at the same time depression of the member 38 will operate through the connection 54 to disengage the detent 55 from the notch of the disk 58, thereby serving to unlock the said disk to permit rotation thereof. Rotation of the operating-shaft 15 against the action of the spring 71 will cause the arm 66 to disengage from the pin 68, which carries the pawl 70, which is arranged to coöperate with the projections 95 62 of the disk 58, and under the yielding action of the actuating-spring 67 the said arm 69 will be rotated, causing the pawl 70 to rotate the disk 58 until the next succeeding projection 59 coöperates with the pawl 60 to 100 momentarily arrest the rotation of the said disk, the projection 56 of the detent 55 during the rotation of the disk subsequently to being unlocked riding upon the periphery of the disk to retain the members 38 and 35 and 105 their attached parts in their relative depressed or actuated positions.

As the crank 26, which is controlled by the arms 22, is actuated during the discharge of each cigar from the carrier it will operate the 110 shaft 30 and the arm 32, fixed thereto, in a manner similar to that described in connection with the operation of the member 35 by the passage of a coin through the corresponding chute 33, the said arm 32 operating to 115 free the coin from the receptacle 39 of the member 38, although the latter will be retained in its depressed position by the detent 55, which at this time will rest upon the periphery of the disk 58. The crank 65 is also 120 connected to the crank 26, and actuation of the latter will cause a rocking motion of the shaft 64, which will disengage the pawl 63 from the projections 62 of the disk 58 to permit rotation of the latter under the yielding 125 action of the spring 67, the pawl 63 immediately engaging the next succeeding tooth when the cigar has been discharged to arrest the rotation of the disk 58. The projections 69 and 62 of the disk 58 will be supplied in 130

numbers corresponding to the number of articles which it is desirable to sell for a coin of a given value, and provided there are a sufficient number of cigars in the hopper the 5 crank 85 may be successively operated to discharge a predetermined number of cigars for a single coin, each actuation of the carrier in such a case causing this disk 58 to be rotated step by step successively until the detent 55 reaches the notch 57 of the said disk, when the latter will become locked and the members 35 and 38 will return to their normal positions, the resetting of these members causing the controlling-arm 45 to be returned to normal position to retain the actuating-pawl 47 out of engagement with the ratchet 48. However, should the supply of cigars become exhausted either prior to or during the successive operations of the carrier to discharge 20 the requisite number of articles according to the value of the coin inserted the arms 22 will not be operated, even though the carrier may be rotated, and consequently the pawl 63, which is actuated thereby, will remain in engagement with the corresponding projections of the disk 58, thereby locking the latter from completing its rotation, and thus maintaining the machine in unlocked condition through the depression of the members 35 and 38. 25

Of course when a coin of comparatively smaller value, which entitles the purchaser to only one article, is inserted in the proper coin-chute 33 the corresponding member 35 operates directly on the controlling-arm 45 to permit the pawl 47 to coöperate with the ratchet 48, which operates the carrier, and the said controlling-arm is immediately restored to normal position by the member 35, when the coin has been ejected therefrom. 30

through the discharge of the cigar from the carrier, and during the single operation of the mechanism in this manner the repeating-disk 58 remains locked and the spring 67 forms a yielding connection between the actuating-arm 69 and the shaft 15, which permits the latter to be actuated independently while the actuating-pawl 70 remains at rest. 35

A vending-machine constructed in accordance with my invention is particularly adapted for use in vending cigars and other frangible or breakable articles which must be protected from injury, for it enables them to be sold directly from the original package in the best manner, and it handles them in such a manner that liability of breakage or other injury is reduced to a minimum, and the device is capable of discharging the cigars in different quantities, depending upon the value of the coin which is inserted therein, 40 by the use of a novel mechanism which enables the devices to be operated one or more times, and, moreover, should the supply of cigars or other articles being vended become exhausted either prior to or during the operation thereof by the purchaser the machine

will remain in unlocked or operative condition to enable the deficiency to be properly supplied when the machine is replenished. However, that portion of my invention relating to the devices for handling and delivering 70 the cigars and the parts related thereto are not claimed in the present application, but are reserved for a divisional application.

I claim as my invention—

1. In a device for vending cigars and similar articles, the combination with a hopper, of a carrier mounted in coöperative relation with the hopper having receptacles for receiving the articles from the hopper, and a device mounted to coöperate with the article in its 80 corresponding receptacle during the operation of the carrier for controlling the locking of the carrier. 75

2. In a device for vending cigars and similar articles, the combination with a hopper, 85 of a carrier mounted in coöperative relation with the hopper having receptacles for receiving the articles from the hopper, controlling means for locking and unlocking the carrier, and a device mounted to coöperate with 90 an article in its corresponding pocket during the operation of the carrier and coöperating with the controlling means for controlling the locking of the carrier.

3. In a device for vending cigars and similar articles, the combination with a hopper, 95 of a delivery-carrier having pockets therein for receiving the articles from the hopper, operating means capable of being connected and disconnected from the carrier, and a device mounted to coöperate with an article in its respective pocket during the operation of the carrier for controlling the delivery operation of the carrier. 100

4. In a device for vending cigars and similar articles, the combination with a hopper, 105 of a carrier having pockets therein for receiving the articles from the hopper, operating means for actuating the carrier, and a device mounted to coöperate with an article in its 110 respective pocket of the carrier for controlling operative connection between the latter and the operating means.

5. In a device of the character described, the combination with a receptacle for the articles to be vended, of a rotatable carrier having pockets therein for receiving the articles from the receptacle, operating means having devices coöperating therewith to control the operation of the carrier, and an arm disposed 115 transversely of the carrier and arranged to coöperate with an article in its respective pocket for controlling the delivery operation of the carrier by the controlling means. 120

6. In a vending-machine, the combination 125 with a hopper or receptacle for the articles to be vended, of a delivery device mounted in coöperative relation with the receptacle for discharging the articles therefrom, operating means for actuating the delivery device ca- 130

pable of being connected and disconnected therefrom, and repeating mechanism for maintaining the operating means and the delivery mechanism in operative connection to 5 permit the latter to be successively operated to deliver a predetermined number of articles.

7. In a vending-machine, the combination with a receptacle for the articles to be vended, and a delivery device coöperatively arranged therewith, of operating means capable of being connected and disconnected from the delivery device for actuating the latter, and repeating mechanism for maintaining the operating means and the delivery device in operative connection to permit the latter to be successively operated a predetermined number of times.

8. In a vending-machine, the combination with a receptacle for the articles to be vended, and a delivery device coöperatively arranged therewith, of operating means normally disconnected from the delivery device, controlling means for establishing an operative connection between the operating means and the delivery device, and means actuated by a coin for operating the controlling means to connect the operating means and delivery device, and means controlled by the discharge 30 of articles from the machine for disconnecting the operating means and the delivery device.

9. In a vending-machine, the combination with a receptacle for the articles to be vended, and a delivery device coöperatively arranged therewith, of operating means for the delivery device, and separately-released devices coöperating with the operating means and controlled by the articles discharged for causing 40 a different number of operations of the delivery device.

10. In a vending-machine, the combination with a receptacle for the articles to be vended, and a delivery device coöperatively arranged therewith, of operating means capable of being connected and disconnected from the delivery device, a device for connecting the operating means to the delivery device to cause a single operation of the latter, and a 50 repeating device capable of maintaining the connection between the operating means and the delivery device to permit a predetermined number of operations of the latter.

11. In a vending-machine, the combination with a receptacle for the articles to be vended, and a delivery device coöperatively arranged therewith, of operating means arranged to coöperate with the delivery device for actuating it, means for controlling the 60 relation between the delivery device and the operating means, a member operating upon the controlling means to permit actuation of the delivery device, means for resetting said member, and devices controlled by the said 65 member for restoring the controlling means

to normal position to render the delivery device inoperative.

12. In a vending-machine, the combination with a receptacle for the articles to be vended, and a delivery device coöperatively arranged therewith, of operating means for the delivery device, a controlling device for connecting and disconnecting the operating means and the delivery device, a member operating upon the controlling means to establish operative connections between the operating means and delivery device, and means controlled by the discharge of an article from the latter for resetting the controlling means.

13. In a vending-machine, the combination with a receptacle for the articles to be vended, and a delivery device therefor, of operating means for actuating the delivery device, controlling means for connecting and disconnecting the operating means and the delivery device, and a repeating device acting upon the controlling means for maintaining operative connection between the operating means and the delivery device to permit a predetermined number of successive operations of the latter.

14. In a vending-machine, the combination with a receptacle for the articles to be vended, and a delivery device therefor, of operating means normally disconnected from the delivery device, a controlling device for establishing connection between the operating means and the carrier, a member operating upon the controlling means for connecting the operating means and the delivery device to permit operation of the latter, a second member also operating upon the controlling device, and a repeating device set into operation by the second member for maintaining an operative connection between the operating means and the delivery device for permitting a predetermined number of successive operations of the latter.

15. In a vending-machine, the combination with a receptacle for the articles to be vended, of an operating-shaft carrying an actuating-arm, a normally inoperative carrier mounted in coöperative relation with the receptacle, an actuating device for transmitting motion from said arm to the carrier to actuate the latter, and a controlling device embodying an arm substantially concentric with said shaft and normally retaining the actuating devices and the carrier out of coöperative relation.

16. In a vending-machine, the combination with a receptacle for the articles to be vended, of an operating-shaft carrying an actuating-arm, a normally inoperative carrier mounted in coöperative relation with the receptacle, a pawl carried by said arm and arranged to coöperate with a ratchet-wheel connected to the carrier, and a controlling-arm having a portion thereon substantially concentric with said shaft and coöoperating

- with the said pawl for disengaging it from the ratchet.
17. In a vending-machine, the combination with a receptacle for the articles to be vended, of an operating-shaft, a carrier mounted in coöperative relation with the receptacle, means for controlling the connection between the operating-shaft and carrier, a repeating device, an actuating device for the repeating device connected to the operating-shaft, locking means for normally retaining the repeating device inactive, and means operated by the repeating device and coöperating with the controlling device for permitting a predetermined number of successive operations of the carrier. 5
18. In a vending-machine, the combination with a receptacle for the articles to be vended, and a delivery-carrier coöperatively arranged therewith, of an operating-shaft, means for controlling the connection between the latter and the carrier, a rotatable disk, a locking device for normally retaining the disk inoperative, a pawl controlling the rotation of the disk when unlocked, an operative connection between the locking device and the controlling means, and an actuating device for the disk connected to the operating-shaft. 10
19. In a vending-machine, the combination with a receptacle for the articles to be vended, and a delivery device coöperatively arranged therewith, of an operating-shaft, devices for connecting and disconnecting the shaft and delivery device, a controlling device for the connecting devices, a repeating-disk, a locking device for normally retaining the disk inoperative, and an actuating device for the said disk embodying a flexible connection between the latter and the shaft for permitting operation of the latter while the disk is locked. 15
20. In a vending-machine, the combination with a receptacle for the articles to be vended, and a rotatable carrier for delivering the articles therefrom, of operating means for actuating the carrier, a repeating device operatively connected to the operating means to receive successive operations therefrom, and means controlled by the discharge of an article from the carrier for locking and unlocking the repeating device at each successive operation. 20
21. In a vending-machine, the combination with a suitable article-delivery device, an operating member therefor normally disconnected therefrom, a coin-actuated member, and means controlled by the operation of the coin-actuated member for placing the delivery device and said operating member in coöperative relation for delivering the articles, of means controlled by the discharge of the articles for causing the coin-actuated member to return to normal position, and prevent operation of the delivery device. 25
22. In a vending-machine, the combination with a suitable article-delivery device, operating means therefor, a coin-actuated member having a coin-receptacle thereon, and means controlled by the coin-actuated member for operatively connecting and disconnecting the delivery device and its operating means, of means controlled by the discharge of the articles for disengaging the coin from the coin-actuated member. 70
23. In a vending-machine, the combination with a suitable article-delivery device, operating means therefor, a lever having a receptacle thereon adapted to hold a coin the weight of which serves to actuate the lever, and means controlled by said lever for coupling and uncoupling the delivery device and its operating means, of a movable arm arranged to disengage the coin from its receptacle on said lever, and means operated only when an article is delivered, for actuating said arm. 75
24. In a vending-machine, the combination with a suitable article-delivery device, and a handle for operating said device to deliver the articles, and a shaft supporting said device and handle, of means for operatively connecting and disconnecting said device and handle embodying a ratchet on one of the parts, a pawl connected to the other part adapted to coöperate with said ratchet, and a controlling device having a portion concentric with the shaft and arranged to coöperate with said pawl and thereby control its relation with the ratchet. 80
25. In a vending-machine, the combination with a suitable article-delivery device, and operating means therefor, of step-by-step repeating mechanism for retaining the machine in condition to permit a predetermined number of successive operations of the delivery device, devices operated by said mechanism after the latter has been advanced a given number of steps for preventing operation of the delivery device, and means actuated by the articles delivered for advancing the repeating mechanism one step for each article actually delivered. 85
26. In a vending-machine, the combination with a suitable article-delivering device, operating means therefor, and a coin-actuated member for placing the article-delivery device in condition for operation to vend the articles therefrom, of means operated by the discharge of the articles for preventing subsequent discharging operation of the delivery device, and serving to retain the coin-actuated member in actuated position to permit subsequent delivery operation of the delivery device by the customer should the delivery device fail to vend an article therefrom. 90
